UNITED STATES PATENT OFFICE.

CHARLES HASSINGER, OF PLYMOUTH, MICHIGAN.

WHIFFLETREE.

SPECIFICATION forming part of Letters Patent No. 225,371, dated March 9, 1880.

Application filed January 8, 1880.

To all whom it may concern:

Be it known that I, CHARLES HASSINGER, of Plymouth, in the county of Wayne and State of Michigan, have invented an Improvement in Whiffletrees, of which the following is a specification.

The nature of my invention relates to certain new and useful improvements in the construction of whiffletrees, by means of which 10 the tugs or traces of the harness may be lengthened or shortened at will without the necessity of going between the horses, or of the use of buckles, with which the harness is usually supplied for that purpose.

15 The invention consists in the peculiar construction and operation of the whiffletree and its combination with a trace-chain, as more fully hereinafter described.

In the drawings, Figure 1 is a perspective 20 view of one end of my improved whiffletree, and Fig. 2 is a like view of the other end, with the locking device open to show the internal construction and the operation of the whiffletrees.

25 Referring to the accompanying drawings, forming a part of this specification, A represents a whiffletree of the ordinary construction, except that it is not provided at its ends with hooks or other ordinary devices to which 30 the harness tugs or traces are usually secured.

On the rear side of each end of this whiffletree there is cut a groove, *a*, to receive the end 35 of a trace-chain, *b*. This groove is covered by a gate, *b'*, hinged to the end band, *c*. To the inner face of this gate there is rigidly secured a stud or lug, *d*. A plate, *e*, is secured centrally upon the near side of the whiffletree, and at each end this plate is provided with a 40 perforated lug, *h*, which, when the gate is closed, passes through the slot in the end thereof, when the hook-latch *i* secures the parts together, and the center piece, gates, and end

bands form a truss to prevent the whiffletree from breaking.

In practice the chain is inserted through 45 the end of the whiffletree into the groove, the gate being open for the purpose. The gate is then closed and fastened, the stud or lug in the inner face thereof entering the link of the chain, which, at its outer or free end, is provided with a hook or other device by which to 50 connect with a tug.

If preferred, instead of a chain, a perforated strap of leather or of spring sheet metal may be employed, as the stud entering any of 55 the perforations would hold the strap in place.

The operation of lengthening or shortening the traces is so obvious that further description is unnecessary.

What I claim as my invention, and desire to 60 secure by Letters Patent, is—

1. A whiffletree provided with a longitudinal recess or groove on its rear side to receive the end of a trace chain or strap, in combination with a device for holding said chain or 65 strap therein, substantially as and for the purpose specified.

2. The combination, with a whiffletree provided with a longitudinal recess or groove on its rear side to receive the end of a trace chain 70 or strap, of a gate or covering for said recess and a lug to hold the chain or strap, substantially as shown and described.

3. In a whiffletree provided with a recess or groove to receive the end of a trace-chain, the 75 combination of the gate *b'*, end bands *c*, and plate *e*, the parts being constructed and secured together and adapted to form a truss for the whiffletree, substantially as set forth.

CHARLES HASSINGER.
